UNITED STATES PATENT OFFICE.

ULYSSES G. LEE, OF CHICAGO, ILLINOIS.

BOOKCASE.

1,307,261.

Specification of Letters Patent. Patented June 17, 1919.

Application filed April 11, 1918. Serial No. 227,956.

To all whom it may concern:

Be it known that I, ULYSSES G. LEE, a citizen of the United States, and resident of Chicago, Illinois, have invented certain and 5 useful Improvements in Bookcases, of which the following is a specification.

My invention comprises a book-case and a reference book-holder, designed for instance to hold a dictionary and a set of 10 books like encyclopedias and it consists in the features and combination, and arrangement of parts hereinafter described, and particularly pointed out in the claims.

In the accompanying drawings;

15 Figure 1 is a perspective view of the invention.

Fig. 2 is a detail view of the means for holding the reference book and adapted to keep the exposed upper parts, or leaves of 20 said book substantially in one plane when the book is open, irrespective of which side the bulk of the leaves may be disposed.

Fig. 3 is a plan view of Fig. 2 with parts in dotted lines.

25 Fig. 4 indicates a condition when the book is stiff and the major portion of its leaves are on one side of the book's center line.

Fig. 5 is a front view of the invention.

Fig. 6 is a vertical sectional view of Fig. 30 5 on the line A—A looking from the right.

Fig. 7 is a side view looking from the right of Fig. 5.

Fig. 8 is a sectional view of a modification.

35 In these drawings 1 indicates the frame which is in the general form of a desk or table. It has an opening 2 in its top through which the reference book, as a dictionary, is exposed to view, and a cover 3 is hinged 40 at the rear of the table and is adapted to close the said opening 2, when the reference book is not in use.

At the front there is a depending leaf *d*, below which there is an opening *d'*, through 45 which a book rack *B* may be drawn to the front to hold the books in inclined position, so that they may be readily accessible. The reference book holder comprises two platforms 4, 5, one for supporting one side of 50 the book, and the other for supporting the other side.

These platforms are lifted or pressed upwardly by springs 6, preferably of spiral form, bearing near the adjacent ends of the platforms, said springs resting upon the 55 partition 7 in the case or frame. For guiding the platforms in their vertical movements, and for holding them level under all circumstances I provide arms 8 and 9, these arms being pivotally connected at their 60 crossing points 10 and pivotally connected respectively to the partition at 11, and to the platform at 12. There are two sets of these arms for each platform, as shown in the plan view, Fig. 3, and I prefer to provide these arms in the form of U-shaped frames, as indicated in dotted lines in said 65 Fig. 3. The free ends of the arms 8 and 9, respectively, engage the platform and the partition or base 7, and are provided preferably with anti-friction rolls to work on the surfaces of said parts. The pivots 11 and 12 of the U-shaped frames are substantially 70 in the same vertical plane with each other, and near the vertical plane of the inner or 75 adjacent edges of the platforms while the free ends of the said U-shaped frames lie at points nearer the outer edges of the platforms, and when the platform is depressed these free ends move toward said outer edge 80 and reach the same when the platform is down, as shown in the right of Fig. 2.

The platforms rise and fall according as the weight of the leaves is lessened or removed therefrom, or is placed thereon, but 85 under all conditions the exposed leaves will be in substantially the same horizontal plane. The platforms automatically will shift their positions relative to each other as the leaves are turned, one platform rising as the other 90 falls, and thus keeping the exposed surfaces in substantially the same plane. In my construction the springs do the lifting of the platforms, and the crossed frames do the guiding and maintain the platforms level 95 under all conditions. No guiding means other than the crossed frames is employed, this function being carried out entirely by the said frames.

Fig. 4 illustrates one of the conditions that 100 must be met. In this figure the book is supposed to be new and stiff at its back, which

would cause the weight of the left hand cover section and the leaves thereon to be applied at the left-hand edge of the platform, instead of being evenly distributed 5 over the platform, but even in this extreme case the platform will be maintained in horizontal position, as shown.

The same thing is true should the platform be set in slightly inclined position. It 10 will be held in this position no matter where the preponderance of weight may be.

The reference book support, as above indicated, is located in the space above the partition, 7, whereas the book rack is located 15 in the space below said partition. The cover 3 besides serving as a closing means for the space occupied by the reference book support controls locking means for the book rack, as will be described later.

20 The book rack is hung on trunnions E. Fig. 7 shows this book rack pulled out with the books exposed in convenient position for reference. The back of the books are exposed at F. Fig. 6 shows this book rack in 25 its closed position.

The trunnions E of the book rack are located at about the center of gravity thereof. When closing book rack is controlled rotatively by the link G, which is pivoted 30 to the case at h and connects with the book rack at H.

The trunnions E have a bearing in the middle of bars I. The front ends of these bars are connected to the links J, the lower 35 ends of which are pivoted to the case at K. The other ends of bars I are connected to a rocker L, which is of U-shape and extends to the left hand end of the case, see Fig. 5, and is there connected to the mechanism at 40 that end. This rocker is pivoted to the case at R.

It will be observed that certain parts which are located at the left hand end of case perform the same function as those at 45 the right hand end, and are therefore given the same numbers, these parts being the trunnion supporting bars I, the links J, and the rocker L being of U-shape has one of its arms at the right and the other at the left of 50 the case.

The rocker L connects with the bars I at opposite ends of the case, and causes them to act in unison. Only the parts which support 55 the book rack and control the direction of its movement are the same at both ends. The link G is at one end only, also the locking dogs M and N. These locking dogs are pivoted to the case at O. The dog M has a handle pin P extending through the case at 60 the right hand end and a slotted plate Q is fastened to the outside of the case, thus limiting the movement of the dog M from which the handle projects. The locking dog N is connected by means of a rod S to a rocker

T. The rod S has a nut and jam nut at its 65 upper end for adjustment, as at S'. Rocker T is pivoted to the case at U, and its inner end is provided with an arm V, which at its opposite end projects upward to make contact with a button W, fastened to the 70 underside of hinged cover 3. This button touches the arm V just as the hinged cover closes and depresses this arm about $\frac{3}{8}$ of an inch. A spring Y lifts up on the rocker T, and the dog N connected thereto when the 75 hinged cover is open. When the cover is open the dog N is held up in its inoperative position by this spring, but when the cover is closed the spring is compressed by rocker T and dog N drops by its own weight into position to serve as a lock for holding the book rack in closed position.

The dog M is shown in Fig. 7 in its engagement with a pin Z which projects from the side of the rocker L. The book rack is 85 thereby locked in the open position shown in Fig. 7, until the latch M is released by lifting the handle pin P.

The rocker L has an arm a, which is connected by a link b, to an arm c. The arm c 90 is fastened to a leaf d hinged to the casing at e. This rocker thereby controls the leaf so that it closes down when the case is closed.

Suitable handles f are provided for pulling book rack out and when in position shown in Fig. 7, the locking dog M drops down into the path of pin Z, and holds the mechanism in position, where it remains until the locking dog is lifted by the handle P. 95

It will be observed that the bars I, links J and rocker L pivoted as described are members of a straight line movement, therefore the trunnions E representing the center 105 of the weight, move along the straight line C and D when the mechanism operates. I prefer to have this straight line slope downward toward the rear, as shown, so that when the dog M is released the book rack 110 rolls back to closed position.

When the book rack is in its closed position the pin Z is engaged by dog N, and is thereby locked until the hinged cover 3 is opened. When this cover is opened the spring Y lifts the rocker T and dog, N, by means of rod S. The dog N is thus lifted out of the path of pin Z and the book rack may be pulled out to its open position. The cover 3 may then be closed, if desired, and locked with a lock and key (not shown). It is then only necessary to release the dog M, whereupon the book rack will automatically move back into the case and will become locked by the pin Z passing to the right of 125 the locking member N, which is free to yield upwardly to allow the pin to pass it when said pin engages with and rides along the

lower edge of the said lock N. After the pin Z passes the rear end of the lock said lock returns to locking position by gravity, where it will remain until the cover 3 is 5 again operated.

Instead of the controlling means for lock N being such as is shown in Fig. 7 I may employ that shown in Fig. 8, in which the rod S' is lifted by a spring Y' when the 10 cover 3 is lifted, exerting its force through a rod S'''. This rod engages under the nuts S' on the rod S''. The rod S''' extends into the opening 2 of the top of the casing, so as to be borne upon by the cover, and be pressed 15 down thereby when the cover is closed, thus eliminating the lifting power of the spring and allowing the rod S'' to fall by gravity and the locking member N to fall into locking position.

20 The view Fig. 8 is a vertical sectional view of the right-hand end of the casing taken longitudinally and hence the view is looking from the front of the casing.

It will be seen from the above that to gain 25 access to the books in the book rack it is necessary to raise the cover 3, whereupon the lock N will be raised to inoperative position, and the book rack then may be drawn outwardly, and held by the latch M, so that the 30 books can be taken out at will. The lifting of the cover of course also exposes the dictionary, or other reference book, mounted on the platforms, and the leaves thereof can be conveniently turned.

35 If the reference book is not needed the cover may be closed and locked while the book rack remains open, or the cover need not be closed until after the book rack is returned into the case.

40 In either event, however, the lock N will be set in its locking position, but if this is done before the book rack is returned this will not interfere with the locking action, because, as above described, the pin Z can 45 pass to the right of the locking member to be locked thereby because of the yielding of the said member.

What I claim is:

1. In combination a casing, a book support adapted to hold a book exposed at 50 an opening in said casing, a cover for said opening and a movable book rack adapted to occupy a closed position within the casing, or to be drawn out therefrom, locking means for the said book rack and a controlling connection for said locking means controlled by the cover or lid, substantially as described.

2. In combination a casing, a book support adapted to hold a book exposed at an 60 opening in said casing, a cover for said opening and a movable book rack adapted to occupy a closed position within the casing, or to be drawn out therefrom, locking means

for the said book rack, and a controlling connection for said locking means controlled by the cover or lid, said connection placing the locking means in inoperative position when the cover is opened and said locking means assuming a position to lock the book 65 rack, when the cover is closed, substantially as described.

3. In combination a casing having an opening in its top for exposing a book, a cover for said opening, a book rack, means for movably supporting the said book rack to assume a position within the casing or to permit the book rack to be drawn forward of said casing to be accessible, a locking device to hold the book rack in closed position, a connection for raising the said lock to inoperative position when the cover is opened and permitting said lock to assume its locking position when the cover is closed, the 70 said connection being yielding to allow the book rack to be moved to its closed position and to be engaged by the lock after the cover is closed and the lock has assumed 75 its locking position, substantially as described.

4. In combination with a casing having an opening, a cover for said opening, a book rack, means for movably supporting the book rack to assume a position in the casing or to be moved forward to present the books to the user, a lock for holding the book rack in its closed position, a connection extending from the lock to be borne upon by the cover to make the lock assume locking position, said connection including a spring to move the lock to inoperative position when the cover is raised, said spring yielding when the cover is closed and the lock assumes locking position, said lock being then capable of yielding independent of the spring to permit the book rack to assume a closed position and to be engaged by the lock, substantially as described.

5. In combination a casing, a book rack, means for movably supporting the book rack to enable it to be drawn forward, or to be moved into the casing, a lock for holding the book rack in its forward position with the books presented to the user, a lock for holding the rack in its closed position, said 100 casing having an opening, a cover for said opening, a controlling connection for the last mentioned lock controlled by the position of the cover, and manually operated means for manipulating the first mentioned 105 lock, substantially as described.

6. In combination a casing having an opening directed forwardly, a book rack, holding the books on edge and in said front opening, trunnions for said book rack about 115 which it turns and by which the rack is supported, bearing members for said trunnions 120

and swinging means for supporting said bearing members and giving the trunnion points a straight line movement to and from position within the casing, substantially as described.

7. In combination a casing, a book rack, trunnions for said book rack, bars forming bearings for the said trunnions, links connecting one end of the bars to the casing and swinging means, connecting the other ends of the bars to the casing to direct the movement of the rack to and from the casing, substantially as described.

8. In combination a casing, a book rack, trunnions for the book rack, bearing members for the trunnions, swinging means connecting the bearing members with the casing, to control the movement of the said bearing members to move the book rack into or out from the casing, and a link connecting the book rack with the casing to turn the said book rack, substantially as described.

9. In combination a casing, a book rack having trunnions, bars in which the trunnions bear, links connected with the forward ends of said bearing bars, extending downwardly therefrom, and pivotally connected with the casing, arms pivotally connected with the rear ends of the bearing

bars, extending upwardly therefrom, and pivotally connected with the casing, said arms and links giving the trunnions a substantially straight line movement to and from the casing and means for turning the book rack as it is moved into and out of the casing, substantially as described.

10. In combination a casing, a book rack, swinging means for supporting said book rack, means for turning the book rack as it swings, a leaf for closing the opening between the book rack and the casing and means for automatically moving said leaf to closing position and for moving it to open position, as the book rack is moved into and out of the casing respectively, substantially as described.

11. In combination a casing having an opening in its front, a book rack, supporting means for the book rack including swinging arms to direct it in its movement to and from the casing, a pivoted leaf to close the opening in the casing above the book rack, and a connection between the said swinging leaf and the swinging arms for automatically operating the leaf as the book rack is moved to and from its closed position, substantially as described.

In testimony whereof, I affix my signature.
ULYSSES G. LEE.
